DELAY DEVICE

The invention relates to a device for delaying a train of signal samples of an electrical signal. The device comprises a sequence of stages which each include a first and a second capacitance interconnected by means of the main current path of at least one transistor. The second capacitance of each stage forms the first capacitance of the succeeding stage, while the input electrode circuit of the transistor includes the first capacitance and its output electrode circuit includes the second capacitance. A switching voltage source is arranged to be connected between the control electrode of the transistor and that terminal of the first capacitance which is not connected to the input electrode of the transistor. In a known arrangement of this kind, as described in Netherlands Patent application No. 6,805,705, corresponding to U.S. Pat. application, Ser. No. 817,690, filed Apr. 21, 1969 and now abandoned the transistor is a field effect transistor. The field effect transistors are interconnected in groups so as to form junction points to which switching signals are applied which are ascendingly shifted in phase in the order of the numbers of the junction points.

Applicant recognizes the problem that when a large number of stages was used satisfactory operation was interfered with by the fact that in each stage a slight degradation of sudden voltage variations occurs. This means that when the input voltage abruptly changes from 0 volts to V volts, the output signal at the output of the arrangement changes from 0 volts to $(V-\delta)$ volts, where δ is the error voltage. If subsequently the input signal remains at the value of V volts, the output signal will also assume this value. The said effect deleteriously affects the frequency characteristic of the device.

It is an object of the present invention to provide a solution of the said problem, and a device according to the invention is characterized in that feedback is provided between the output electrode of the transistor of at least one of the stages and the input electrode circuit of the said stage, by which feedback during the transfer of information between the first and the second capacitances of the said stage there is produced in series with the input electrode circuit a voltage which is a fraction of the voltage set up at the output electrode of the transistor and which has the same polarity as the threshold voltage of the transistor in the conductive condition thereof.

The invention is based on the recognition that the said signal degradation is due to the fact that the threshold voltage of a transistor depends on the transferred signal value ΔV . When a comparatively small number of stages is used, this effect will not be troublesome, but when a large number of stages, for example several hundreds of stages, are used, it will be highly troublesome. The effect will be particularly strong when the transistors used are field effect transistors. This is due to the fact that electrostatic reaction takes place from the drain electrode by way of the substrate on the boundary region between the source electrode and the drain electrode of the field effect transistor used, and that on the other hand the length of the depletion layer slightly depends on the voltage at the drain electrode. In field effect transistors having a high-resistivity substrate the electrostatic reaction is the dominant factor, whereas in field effect transistors having a low-resistivity substrate the second effect is dominant.

An embodiment of the invention will now be described, by way of example, with reference to the accompanying diagrammatic drawings, in which:

FIG. 1 shows the known arrangement,

FIG. 2 shows the voltage waveforms at different points in the known arrangement,

FIG. 3 shows an embodiment of an arrangement according to the invention and

FIG. 4 shows the voltage waveforms at various points in the arrangement of FIG. 3.

In the known delay device shown in FIG. 1, the main current paths of field effect transistors $T_0, T_1, T_2, \dots, T_n$ are connected in series. A capacitor C_0 has been connected between the drain and the gate of the transistor T_0 . A capacitor C_1 has

been connected between the drain and the gate of the transistor T_1 . A capacitor C_2 has been connected between the drain and the gate of the transistor T_2 . A capacitor C_n has been connected between the drain and the gate of the transistor T_n .

5 The gate of the transistor T_1 has been connected to an output S_2 of a switching voltage source S_0 . The gates of the transistors T_0 and T_n have been connected to an output S_1 of the switching voltage source S_0 . A diode D_n has one terminal connected to the drain of the transistor T_n and the other terminal connected to the output S_2 of the switching voltage source S_0 . The source of the transistor T_0 has been connected to a point of constant potential through the series combination of a resistor T_0 , an input voltage source V_i and a direct-voltage source E_1 .

10 15 The operation of the known arrangement will be described with reference to FIG. 2. FIGS. 2b and 2c show the voltage waveforms at the outputs S_2 and S_1 , respectively. These voltages are symmetrical square-wave voltages having a maximum of 0 volt and a minimum of $-E$ volts. During the time in which the voltage at the points S_1 is negative with respect to earth, i.e. during time intervals $\tau_2, \tau_4, \tau_6, \tau_8$, etc. in FIG. 2b, information about the value of the input signal V_i is transferred to the capacitor C_0 . During the time interval τ_2 the input signal V_i is small, see FIG. 2a, whereas during the time interval τ_4 and the following time intervals the input signal V_i is large. During the time interval τ_2 there will flow through the transistor T_0 a current of about V_i/R_0 amperes, where V_i is the value of the input signal during the time interval τ_2 under consideration and R_0 is

20 25 the resistance of the resistor R_0 of FIG. 1. The said current will cause the voltage at the drain of the transistor T_0 to increase by an amount ΔV_1 , see FIG. 2d. During the time interval τ_3 the capacitor C_0 is discharged through the transistor T_1 until the voltage across this capacitor has become equal to $-(E-V_d)$

30 35 volts, where V_d is the threshold voltage of the transistor T_1 , the value of this threshold voltage being determined by the signal value ΔV_1 . During the time interval τ_4 charge is again supplied to the capacitor C_0 through the transistor T_0 , so that the voltage at the drain of the transistor T_0 will rise by an amount of ΔV_2 volts, see FIG. 2d. During the time interval τ_5 the capacitor C_0 is discharged through the transistor T_1 until the voltage across this capacitor has become equal to $-(E-V'_d)$ volts, where V'_d is that threshold voltage of the transistor T_1 which is associated with the signal value ΔV_2 . It has been

40 45 found that the threshold voltage V'_d associated with the signal value ΔV_2 exceeds the threshold voltage V_d associated with the signal value ΔV_1 by an amount of δ volts. This means that the voltage drop across the capacitor C_0 which occurs during the time interval τ_5 will be equal to $(\Delta V_2-\delta)$ volts instead of to ΔV_2 volts.

50 55 At the instant at which the time interval τ_6 begins the voltage at the drain of the transistor T_0 will be equal to $\{-(2E-V_d)+\}$ volts, see FIG. 2d. At the end of the said time interval the voltage at the drain of the transistor T_0 will be equal to $\{-(2E-V_d)+\delta+\Delta V_2\}$ volts. Consequently, the voltage drop across the capacitor C_0 will be equal to ΔV_2 volts during this time interval.

During the time interval τ_3 the capacitor C_1 is charged through the transistor T_1 until the voltage across this capacitor has risen by an amount of ΔV_1 volts, see FIG. 2e. During the time interval τ_4 the capacitor C_1 is discharged through the transistor T_2 until the voltage across this capacitor has become equal to $-(E-V_d)$ volts, where V_d is the threshold voltage of the transistor T_2 associated with the signal value ΔV_1 . During

60 65 the time interval τ_5 the capacitor C_1 is charged through the transistor T_1 . The voltage rise across the capacitor C_1 will be equal to the voltage drop across the capacitor C_0 during the time interval under consideration. Consequently, the said voltage rise will be equal to $(\Delta V_2-\delta)$ volts. During the time interval τ_6 the capacitor C_1 is discharged through the transistor T_2 until the voltage across this capacitor has become equal to $-(E-V_d)$ volts, where V''_d is the threshold voltage of the transistor T_2 associated with the signal value $(\Delta V_2-\delta)$. Since δ is much smaller than ΔV_2 , we have to a good approximation:

70 75 $V''_d = V_d$. This means that the voltage drop across the capaci-

tor C_1 during the time interval τ_6 will be equal to $(\Delta V_2 - 2\delta)$ volts instead of ΔV_2 volts, as it should have been. A simple calculation shows that the voltage drop across the capacitor C_n of the capacitive store of FIG. 1, which voltage drop corresponds to the voltage drop $(\Delta V_2 - \delta)$ volts across the capacitor C_0 during the time interval τ_5 , will be equal to $(\Delta V_2 - n\delta)$ volts, where n is the number of the capacitor C_n . However, this will hold only if $n \cdot \delta$ is small compared with ΔV_2 . If $n \cdot \delta$ becomes comparable to ΔV_2 , i.e. if n is large, the corresponding voltage drop will be equal to $(1 - \delta)^n$ volts. However, if $n \cdot \delta$ becomes comparable to the signal value ΔV_2 , second-order and third-order effects also will occur. This means that in contradistinction to the example discussed with reference to FIGS. 2d and 2e in which one signal value only was not correct (see the interval τ_5 of FIG. 2d and the interval τ_6 of FIG. 2e), at least two successive signal values will not be correct, as is shown diagrammatically in FIG. 2f. In this Figure the signal values during the intervals τ_m and τ_{m+2} are not correct. During the interval τ_m the signal value is equal to $(\Delta V_2 - \delta_{11})$ volts, and during the interval τ_{m+2} it is equal to $(\Delta V_2 - \delta_{22})$ volts. Not before the interval τ_{m+4} will the signal value be correct and equal to ΔV_2 volts.

FIG. 3 shows a delay device according to the invention. It comprises transistors $T_0, T_1, \dots, T_n$ and T_{n+1} the main current paths of which have been connected in series. Capacitors $C_0, C_1, \dots, C_n$ and C_{n+1} have been connected between the drain and gate electrodes of the transistors $T_0, T_1, \dots, T_n$ and T_{n+1} , respectively. The source of the transistor T_0 has been connected to a point of constant potential through the series combination of a resistor R_0 and a signal voltage source V_1 . The gate of the transistor T_0 has been connected to an output S_1 of a switching voltage source S_0 , and the gates of the transistors T_1 and T_{n+1} have been connected to an output S_2 of the switching voltage source S_0 . The gate of the transistor T_n has been connected to the output S_1 of the switching voltage source S_0 through a resistor R_2 . The drain of the transistor T_{n+1} has been connected, through a diode D , to the output S_1 of the switching voltage source S_0 and also, through a follower circuit F and a resistor R_1 , to the gate of the transistor T_n . The operation of the delay device of FIG. 3 will be described with reference to FIG. 4.

FIGS. 4a and 4b show the voltage waveforms at the outputs S_1 and S_2 of the switching voltage source. FIG. 4c shows the voltage at a point B_n of the delay device and FIGS. 4d and 4e show the charges present in the capacitors C_n and C_{n+1} respectively as functions of time. During the time interval τ_0 information from a capacitor preceding the capacitor C_{n-1} is transferred to the capacitor C_{n-1} . It is assumed that during this interval no charge is transferred to the capacitor C_{n-1} . This means that the final charge in this capacitor is equal to $-C(E - V_d)$ coulombs, where C is the capacitance of the capacitors C_{n-1}, C_n and C_{n+1} . It is further assumed that during the same time interval no charge is transferred between the capacitors C_n and C_{n-1} . This means that during the said interval the voltage at the point B_n will be equal to $-2p(E - V_d)$ volts, where p is equal to the quotient $(R_2/R_1 + R_2)$. This means that during the said interval the charge in the capacitor C_n will be equal to

$$Q_n(0) = -C(1-2p)(E - V_d) \text{ coulombs} \quad (1)$$

During the time interval τ_1 no charge is transferred between the capacitor C_{n-1} and the capacitor C_n , since during this interval the transistor T_n will not be conductive. This means that the charge $Q_n(0)$ will be equal to the charge $Q_n(0)$, see FIG. 4d. It is assumed that during the time interval τ_2 a charge equal to $(1-a) \cdot \Delta V \cdot C$ is transferred to the capacitor C_{n-1} , where a is an attenuation factor and ΔV is the value of the signal sample as initially applied to the input of the delay device. During the same time interval no charge transfer takes place between the capacitors C_n and C_{n+1} , so that the charge states of these capacitors will remain unchanged, see FIGS. 4d and 4e. During the time interval τ_3 no charge transfer takes place between the capacitors C_{n-1} and C_n . A charge equal to $(1-a) \cdot \Delta V \cdot C$ coulombs is supplied to the capacitor C_n . Hence, the final charge in this capacitor will be equal to

$$Q_n(3) = \{-(1-2p)(E - V_d) + (1-a)\Delta V\} \text{ coulombs} \quad (2)$$

see FIG. 4d. During the time interval τ_4 a charge transfer takes place between the capacitors C_n and C_{n+1} . At the beginning of this time interval the charge in the capacitor C_{n+1} is equal to $-C(E - V_d)$ coulombs, see FIG. 4e, whilst the initial charge in the capacitor C_n is given by the relation (2). At the end of the interval under consideration, the voltage across the capacitor C_{n+1} is desired to be equal to $-(E - V_d) + \Delta V$ volts, since in this event the attenuation involved will be compensated. This will be achieved if a charge equal to $C \cdot \Delta V$ coulombs is transferred from the capacitor C_n to the capacitor C_{n+1} . Consequently, the final charge in the capacitor C_n will be equal to

$$Q_n(4) = C \{-(1-2p)(E - V_d) + (1-a)\Delta V - \Delta V\} \text{ coulombs} \quad (3)$$

see FIG. 4d. On the other hand, if the final voltage across the capacitor C_{n+1} is equal to $(E - V_d) + \Delta V$ volts, the voltage at the point B_n will be equal to $-2p(E - V_d) + p\Delta V$ volts, see FIG. 4c. The voltage at the source of the transistor T_{n+1} will be equal to $-(E - V_d)$ volts during the charge transfer. Hence the voltage across the capacitor C_n will be equal to $-(1-2p)(E - V_d) - p\Delta V$ volts and consequently the charge in the capacitor C_n will be equal to

$$Q_n' = C \{-(1-2p)(E - V_d) - p\Delta V\} \text{ coulombs} \quad (4)$$

A closer consideration of the relations (3) and (4) will show that by making $p=a$ the desired compensation for the attenuation is obtainable.

In the delay device shown in FIG. 3, the compensation circuit has been included in the final stage ($n+1$). For practical reasons it may be desirable for the compensation circuit to be included not in the final stage but in one of the preceding stages. In this case, however, it is desirable to make $p > a$ with some consequent overcompensation which will enable the correct frequency characteristic to be obtained at the output of the delay device. When the delay device comprises a large number of stages, several stages may be provided with overcompensation, which additionally achieves an improved signal-to-noise ratio of the delay device. Instead of in series with the capacitor C_n the resistor R_2 may be connected between the gate of the transistor T_{n+1} and the output S_2 of the switching voltage source S_0 with the interposition of an inverter. Further, instead of the resistors R_1 and R_2 a capacitor C_x may be connected between the source of the transistor T_{n+1} and the source of the transistor T_n in which case the source of the transistor T is also connected through a resistor to a point of constant potential. The feedback factor p will in this case be equal to (C_x/C) , where C is the capacitance of the capacitor C_n and C_x is the capacitance of the aforementioned capacitor. Also, the follower circuit shown in FIG. 3 may be replaced by any other follower circuit. In addition, the device shown in FIG. 3 is suitable to be at least partially integrated in a semiconductor body.

What is claimed is:

1. A device for delaying a train of signal samples of an electrical signal, comprising a plurality of interconnected stages, each stage comprising a transistor having a control input and a main conduction path comprising a signal input and a signal output, wherein current through the main conduction path is a function of voltage between the control input and the signal input thereof, each stage further comprising a capacitor and first means for connecting the capacitor across the control input and signal output of the transistor, the device further comprising second means for serially connecting the main conduction paths of the transistors in all of the stages, means connected to the control inputs of the transistors in all of the stages for receiving switching pulses having a magnitude sufficient to render alternate transistors of the device conducting, and feedback means connecting the signal output of a transistor in a selected stage of the device to the signal input of the transistor in the selected stage for feeding a portion of the voltage on the capacitor of the selected stage to the signal input terminal of the associated transistor.

2. A device as claimed in claim 1, further comprising a first resistor serially connected with the capacitor of a stage preceding the selected stage and the signal input of the transistor in the selected stage, a second resistor connected to the first resistor and the capacitor of the stage preceding

selected stage and a non-inverting amplifier having an output connected through the second resistor to the first resistor and an input connected to the signal output of the transistor in the selected stage.

3. A device as claimed in claim 2, wherein the non-inverting amplifier comprises a field effect transistor, the drain and gate

electrodes of which form the output and input respectively of the non-inverting amplifier circuit.

4. A device as claimed in claim 1, wherein a substantial portion of the device is integrated in a semiconductor body.
